UNITED STATES PATENT OFFICE

AARON ELKONIN, OF SAN PEDRO, CALIFORNIA

DESIGN FOR A CLOCK FACE

Application filed September 19, 1932. Serial No. 44,991. Term of patent 14 years.

To all whom it may concern:

Be it known that I, AARON ELKONIN, a subject of the Government of Russia, having declared my intention of becoming a citizen of the United States, residing at San Pedro, in the county of Los Angeles and State of California, have invented a new, original, and ornamental Design for a Clock Face, of which the following is a specification, refer-

ence being had to the accompanying drawing, forming part thereof.

The figure in the drawing is a face view of a clock face showing my design.

My design is of negligible thickness.

I claim:

The ornamental design for a clock face as shown and described.

AARON ELKONIN.
